UNITED STATES PATENT OFFICE.

WILLIAM H. MINER, OF CHICAGO, ILLINOIS.

DRAFT-RIGGING FOR RAILWAY-CARS.

1,070,053.

Specification of Letters Patent. Patented Aug. 12, 1913.

Application filed February 24, 1913. Serial No. 750,162.

To all whom it may concern:

Be it known that I, WILLIAM H. MINER, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of efficient operation, and one adapted to afford an easy initial movement in practical operation.

In the drawings forming a part of this specification Figure 1 is a side elevation partly in longitudinal section on line 1—1 of Fig. 2 of a draft rigging embodying my invention. Fig. 2 is a plan view partly in horizontal section on line 2—2 of Fig. 1.

Referring to the drawings 3, 3 represent draft sills or parts of the car frame to which the draft rigging is attached, 4 the end sill, 5 the buffer block, 6 the draw-bar carry-iron, 7 the tie plate, 8 the front stop members having the front stop shoulders 9, 9, 10, 10 the rear stop members having the rear stop shoulders 11, 11, 12 the draw bar, 13 the draft yoke, 14 the coupler key connecting the draft yoke to the draw bar, 15 the front follower, and 16 the rear follower. All the foregoing parts are of well known construction.

Seated within the lateral opening 17 of the draft yoke and between the front and rear followers 15 and 16 respectively is the draft gear 18. The draft gear comprises a shell 19, and contained parts hereinafter described, a spring 20 seated between the shell 19 and the front follower 15, and springs 38, 39 seated between the shell 19 and the rear follower 16. The shell 19 comprises the friction cylinder 22 and the spring cage 23. Within the friction cylinder are the friction shoes 24, preferably three in number, and in annular arrangement, and the wedge 25 and the antifriction rolls 26, one of which is interposed between each friction shoe and the wedge.

Within the spring cage 23 is the movable double-faced spring seat 27, the said spring seat being forwardly provided with a boss 28, which is adapted to engage the friction

shoes 24 upon the compression of the spring 29, which is seated within the said boss 28 and between the movable spring seat 27 and the friction shoes. Between the rear end 30 of the spring cage and the rear face of the movable spring seat 27 is seated a plurality of springs, preferably comprising two sets of two springs each, the outer springs 31, 31 each having nested within it an inner spring 32. 60 65

The spring cage is interiorly provided at either side and at its forward end with a stop bolt 33 adapted to limit the forward movement of the movable spring seat 27. A connecting bolt 34 connects the wedge 25 70 with the movable spring seat 27. The spring 20 is disposed about the friction cylinder 22 inclosing the same, and is seated at its rear end against the shell at the forward face 35 of the spring cage 23, and at 75 its forward end against the front follower 15.

The shell 18 is rearwardly provided with a rearwardly opening recess 36, the inner face of which is provided with bosses 37, 80 preferably two in number. Around each boss and between the spring cage at its one end and the rear follower at its other end is seated an inner spring 38 and an outer spring 39. 85

When the parts of the draft gear are in normal position, as illustrated in the drawings, a space, as indicated at the numeral 40 in Fig. 2, is provided between the rear follower and the rear ends of the shell so as to permit compression of the springs 38, 38 and 39, 39 within the said recess 36 before the shell comes into engagement with the rear follower 16. A space is also provided, as indicated at the numeral 41 between the wedge 95 25 and the front follower 15, to permit a partial compression of the encircling spring 20 before the front follower 15 engages the wedge 25. It will thus be seen that on movement of the draw bar the inclosing spring 20 at the forward end of the gear and the springs 38 and 39 at the rearward end of the gear serve as preliminary compression resisting members, and afford an easy initial action that insures the easy starting and stopping of trains of cars to which draft rigging embodying this gear is applied. On compression of the springs 38 and 39 within the recess 36 the shell comes 100 105 into engagement with the rear follower 16. 110 It will thus be seen that the movement of the draw bar is resisted by the closing spring.

20 at the forward end of the gear and the
springs 38 and 39 at the rear end of the
gear; that upon partial compression of the
spring 20 the front follower 15 will engage
5 the friction members within the friction cylinder, and that the friction shoes 24 thereof in their rearward movement will compress the preliminary spring 29 until the
10 shoes 24 engage the boss 28, and thereupon the friction members and the spring members within the shell will come into action. Meanwhile the movement of the draw bar is being resisted by the springs 38 and 39 within the recess 36 until the shell engages
15 the rear follower, and the spring 20 also continues to compress after the engagement of the front follower with the friction mechanism.

I claim:

20 1. In a draft rigging for railway cars, the combination with the draw bar, followers and draft yoke, of a draft gear interposed between said followers, the said draft gear comprising a shell, said shell being
25 composed of a friction cylinder and spring

cage, a friction mechanism within the friction cylinder, springs within the spring cage, and a spring encircling the friction cylinder seated at one end against the shell and at the other end against a follower.

30

2. In a draft rigging for railway cars, the combination of a draw bar, draft yoke, front and rear followers, of a draft gear disposed between said followers, said draft gear comprising a shell, friction mechanism 35 and spring mechanism within said shell, a spring seated between said shell and the front follower, and further springs seated between said shell and the rear follower.

3. In a draft gear, a friction cylinder and 40 a spring cage, springs within the spring cage, friction mechanism within the friction cylinder, and a spring surrounding the friction cylinder and seated against the spring cage.

WILLIAM H. MINER.
